UNITED STATES PATENT OFFICE

2,450,070

MARINE SEA CHEST SAND SEPARATOR.

Bruce R. Wright, Lakewood, Ohio, assignor to
 Centrifix Corporation, Cleveland, Ohio, a corporation of Ohio

Application November 2, 1944, Serial No. 561,619

4 Claims. (Cl. 114—0.5)

1

This invention relates to an improvement in cooling system for marine motors.

More particularly this invention contemplates a cooling system for marine motors in small craft and especially such as are used for landing on sandy beaches or which travel in shallow water.

Heretofore it has been customary in connection with the cooling of the motors in small craft, such as the so-called landing craft which are adapted to land on open beaches, to provide within the hull a so-called sea chest to which sea water is admitted and from which the cooling water for the motors is drawn. Such sea chests are provided with baffles or settling means and it is intended that any sand stirred up by the craft's propeller and entering the chest with the water will settle so that clean water can be drawn from the chest for the cooling of the motors.

In practice, however, it has been found that the sea chests as heretofore provided do not effectively serve the purpose in that the settlement of sand therein, even under quiet sea conditions, is not complete; and to the extent that settlement occurs sand builds up in the chest rapidly and carries over into the cooling system of the motors causing clogging of their cooling systems and defeating the purpose of separation in the sea chest.

Now in accordance with this invention there is provided in combination with a sea chest, means for effectively separating sand from the water entering the chest and for removing the separated sand from the chest to insure the supply of clean water to the cooling system of the motors under any conditions.

Having now indicated in a general way the nature and purpose of the invention, I will proceed to a detailed description of a preferred embodiment thereof with reference to the accompanying drawings in which:

Figure 1 is a side view partly broken away and partly in section of an embodiment of this invention;

Figure 2 is a sectional view on the line 2—2 of Figure 1;

Figure 3 is a sectional view on the line 3—3 of Figure 1;

Figure 4 is a side view of a modified embodiment of this invention;

Figure 5 is a sectional view on the line 5—5 of Figure 4; and

Figure 6 is a diagrammatic view showing the assembly of the device according to this invention with the cooling system of an engine.

In the several figures variously and more par-

5 ticularly referring to Figures 1—3 and 6, 1 indicates the hull of a boat or ship, for example, of a type adapted and intended to be operated in shallow water or run up on a beach. Within the hull 1 is formed a water chamber or sea chest 2 receiving sea water through an opening in the hull, which may extend throughout the length and height of the chest to allow free communication with the sea, and which is covered with a 10 screen or strainer 3.

Within the chest 2 are positioned a pair of fixed centrifugal devices or tuyères 5, 5.

The tuyères 5, 5 are identical and comprise 15 cylindrical chambers provided with outlet openings 6 in their tops and having their bottoms so formed as to provide sumps 7. The tuyères are further provided with a series of tangential passages 8 about their circumferences and spaced above their bottoms. The passages 8 may be 20 formed by slitting the material of the tuyères to form tongues 9 and bending the tongues inwardly as shown, for example, in Figure 2.

The outlet openings 6 communicate with head 25 chambers 10 which open into a conduit 11 which extends without the chest 2 and is connected with a pump 12 delivering to a heat interchanger 13. The sea water delivered to the heat interchanger 13 serves to cool the fresh water circulated through the water jacket of an internal 30 combustion engine 14 and is discharged overside from the heat interchanger through a pipe 15.

The sumps 7 formed in the bottoms of the tuyères 5, 5 are connected by pipes 16 through a Y fitting 17 to a pipe 18 which extends upwardly 35 outside of the chest 2 and for discharge outside of the hull 1. Extending upwardly from the Y fitting concentrically within the pipe 18 is a small pipe 19 adapted to be connected with a pump (not shown) for the delivery therethrough into 40 pipe 18 of a stream of water under relatively high velocity.

In operation of the device described with reference to Figures 1—3 and 6, sea water filling the chest 2 will be drawn by pump 12 into the tuyères 45 5, 5 through the radial openings 8 and as a consequence will have a whirling motion as well as an upward travel within the tuyères.

If now the water in the chest 2 carries sand in suspension, as it will where the vessel is operated in shallow water or is beached; due to the disturbing effect of the propellers, the whirling motion of the water in the tuyères sets up vortex action with the result that sand is drawn inwardly and downwardly to the bottom of the tuyères and falls into the sumps. Water free

from sand passes upwardly and out through the openings 6. Sand thrown against the walls of the tuyères will fall toward their bottoms and ultimately reach the sumps 7, from which the sand together with some water will pass through pipes 16 into the Y fitting 17.

Water at high velocity emitting from pipe 19 will set up an ejecting effect with the result that the sand from the bottoms, or sumps 7, of tuyères 5, 5 will be discharged overside through pipe 18 and sand will not collect or build up in the tuyères or in chest 2.

The water issuing from the tuyères through openings 6 will be free from sand and hence the conduit 11 and pump 12 will not be abraded and clogging of the heat interchanger 13 will be avoided.

Referring now to Figures 4 and 5 which show a modification of this invention, the tuyères 5, 5 are omitted from chest 2 and conduit 11' leading to pump 12 is connected directly to the upper part of the chest. Within the chest and parallel to the opening in the hull is a baffle plate 4. Lying on, or adjacent to, the bottom of the chest, which slants downwardly toward the opening in hull 1 are a series of casings 20 extending laterally through the baffle within the chest.

The casings 20, which are preferably circular, are closed at their upper end, open at their lower end and are provided with longitudinally extending slots 21, or a series of openings in their bodies, in their extension inside of the baffle 4.

Extending into the casings 20, through their upper ends, and concentric therewith are small pipes 22 connected to a manifold 23 supplied with water from a pump (not shown) through pipe 24 for discharge from pipes 22 at high velocity.

In the operation of the modification shown in Figures 4 and 5, sand entering chest 2 with sea water will settle to the bottom of the chest behind the baffle 4, which will serve to limit the effect of motion of the vessel on the water behind the baffle and hence will promote the settlement of sand. The discharge of water at high velocity through pipes 22 will cause an ejecting effect, which will act to draw sand from the bottom of the chest into the casings 20 through slots 21 and eject it from the casings through the opening in the hull, as shown by the arrow Figure 5, all with the result that the water passing from the chest through conduit 11' will be freed from sand by settlement in the chest and the settled sand will be ejected from the chest with avoidance of building up to interfere with settlement and resuspension from the motion of the vessel.

It will be appreciated that for setting up the ejecting effect any fluid at high velocity, as air, may be used in place of water as described above for illustrative purposes and that various modifications may be made in the structure described in detail above without departing from the scope of the appended claims.

What I claim and desire to protect by Letters Patent is:

1. In a cooling system for marine motors, in combination, a hull, a sea chest within the hull and having communication through the hull for the entry of sea water, a tuyère comprising a body provided with tangential openings mounted within said chest and adapted to receive through said tangential openings water carrying sand whereby a whirling motion will be imparted to water carrying sand within said tuyère to effect

separation of sand and water, means for drawing sea water into the sea chest and for the withdrawal of water from the top of said tuyère, a fluid actuated ejector in communication with the bottom of said tuyère for the withdrawal of sand therefrom and means connected with said ejector for the discharge of sand without said chest.

2. In a cooling system for marine motors, in combination, a hull, a sea chest within the hull and having communication through the hull for the entry of sea water, a tuyère comprising a top, a bottom, and a cylindrical body portion provided with tangential openings mounted within said chest and adapted to receive through said tangential openings water carrying sand whereby a whirling motion will be imparted to water carrying sand within said tuyère to effect separation of sand and water, said openings being located above the bottom and below the top of the tuyère, the top of said tuyère having a downwardly extending annular flange forming an outlet opening concentric with the body portion opening into an outlet conduit, a fluid actuated ejector in communication with the bottom of said tuyère for the withdrawal of sand therefrom means connected with said ejector for the discharge of sand to the outside of the hull and means for causing water to flow into the chest and through the outlet conduit.

3. In a cooling system for marine motors, in combination, a hull, there being an opening in one side of the hull, a sea chest constructed within the hull about said opening and having its bottom slanting downward toward the lower point of the said opening, there being a settling chamber in the chest having a wall separating the settling chamber from the chest provided with openings spaced from the bottom of the settling chamber through which the water passes to the settling chamber from the chest to permit the sand to settle on the bottom of the settling chamber, an outlet conduit leading from the upper portion of the settling chamber for the delivery of water to the cooling system, a fluid actuated ejector having an inlet for sand communicating with the bottom of the settling chamber and an outlet for the discharge of sand to the exterior of the hull, and means for delivering ejecting fluid to the ejector.

4. In a cooling system for marine motors, in combination, a hull, a sea chest within the hull and having communication through the hull for the entry of sea water, a fixed centrifugal device within said chest having openings above the bottom and below the top thereof through which water flows carrying sand for the separation of sand carried thereby, tangential members adjacent to said openings whereby a whirling motion will be imparted to the water in the centrifugal device to cause the sand to settle to the bottom thereof, a conduit connected to said centrifugal device above the openings for the passage of water therefrom to the cooling system, means for drawing sea water through the sea chest and through the centrifugal device into the conduit and for delivering the water to the cooling system, a fluid actuated ejector in communication with the bottom of the centrifugal device below said openings for the withdrawal of sand therefrom, an outlet from the ejector for the discharge of sand to the exterior of the hull and means for delivering ejecting fluid to the ejector.
